UNITED STATES PATENT OFFICE

149,551

DESIGN FOR A PASTRY IMPLEMENT

Paul R. Gruber, Waterbury, Conn.

Application November 26, 1946, Serial No. 135,111

Term of patent 7 years

(Cl. D44—29)

To all whom it may concern:

Be it known that I, Paul R. Gruber, a citizen of the United States, residing at Waterbury, in the county of New Haven and State of Connecticut, have invented a new, original, and ornamental Design for Pastry Implements, of which the following is a specification, reference being had to the accompanying drawing, forming a part thereof.

Fig. 1 is a plan view of a pastry implement, showing my new design.

Fig. 2 is an edge view of the same as viewed from one end, and,

Fig. 3 is an edge view as viewed from the side.

I claim:

The ornamental design for a pastry implement, as shown.

PAUL R. GRUBER.
